UNITED STATES PATENT OFFICE.

HENRY L. DIXON, OF PITTSBURG, PENNSYLVANIA.

GLASS-POT FURNACE.

SPECIFICATION forming part of Letters Patent No. 691,250, dated January 14, 1902.

Application filed June 4, 1901. Serial No. 63,088. (No model.)

To all whom it may concern:

Be it known that I, HENRY L. DIXON, of Pittsburgh, in the county of Allegheny and State of Pennsylvania, have invented a new and useful Glass-Pot Furnace, of which the following is a full, clear, and exact description, reference being had to the accompanying drawings, forming part of this specification, in which—

10 Figure 1 is a top plan view of my improved regenerative furnace, partly on the line I I of Fig. 2. Fig. 2 is a longitudinal section on the irregular line II II of Fig. 1. Figs. 3 and 4 are cross-sections on the lines III III and IV IV, respectively, of Fig. 1.

15 My invention relates to glass-pot furnaces wherein a regenerative heating system is employed, and is designed to cheapen and improve the construction of such furnaces and increase their capacity and, further, to facilitate the applying of the regenerative heating system to old furnaces.

20 Heretofore in regenerative pot-furnaces the inlet and outlet ports for the gases and products have been located at opposite sides of the furnace near the side walls, and for this reason the number of pots which could be used in a furnace was reduced by this location of the ports, a sixteen-pot furnace actioning only fourteen pots, with the consequent decrease in capacity. This arrangement of the ports was deemed necessary on the theory that if the inlet and outlet ports should be arranged nearer to each other the 25 gases would short-circuit, and thus pass out without efficient extraction of their heat. In applying this regenerative system to an old furnace it was necessary to tear the entire furnace down and rebuild it. My invention 30 overcomes these difficulties and enables the full number of pots to be used. It is based upon the fact which I have found in practice that the draft or outlet flue simply relieves the excess pressure in the furnace and that 35 hence there is no short-circuiting of the gases where the inlet and outlet flues are closely adjacent. In these furnaces the dampers in the stack-flue are always adjusted to prevent any sucking out of the gases from the furnace, since otherwise the furnace will become 40 chilled. The result, therefore, is that the car-

bonic-acid gas and products of combustion settle over the floor of the furnace-chamber, and as the heated products rise from the ports they expand rapidly and fill the entire 55 chamber. The entering gases consequently burn and spread throughout the upper part of the chamber, from which they descend to the outlet-ports. My invention is based upon this fact; and it consists in placing the regenerative ports inside the lines of the pots, thus allowing the full number of pots to be used. It further consists in assembling the regenerative flues within the "cave" used in these furnaces and extending transversely beneath the furnace on a diameter thereof, and also in the construction and arrangement of the parts, as hereinafter more fully described, and set forth in the claims.

25 In the drawings, 2 represents a pot-furnace of the ordinary form and arranged to contain an annular row of pots on the bench 3.

The regenerators which I employ are located exteriorly to the furnace, as shown in Figs. 1 and 2, and these regenerators may be arranged in any desired manner to preheat the air or combustible gases, or both, though I prefer the arrangement shown. In this form 44 are air-regenerators, and 55 gas-regenerators. The gas-supply flues 66 lead to the 80 point *x* where the ordinary reversing-valve is located, and similarly the air-supply flues 77 lead to the point *y* where the air-valve is used.

20 The set of regenerators covers a space much wider than the tunnel beneath the furnace, 85 and the flues connecting these regenerators to the furnace-ports consequently extend inwardly and toward each other, and the air and gas flues are preferably arranged one above the other within the tunnel. Thus in Fig. 1 90 88 are the air-inlet ports, and 99 the gas-inlet ports, these being used alternately in the usual manner. The connecting-flues 10 extend horizontally through the tunnel to the gas-inlet ports and connect with the upper 95 part of the gas-regenerators through flues 11, located between the bridge-wall 12 and the front of the regenerative chamber. The gas-supply flue 6 leads into the lower part of the regenerator and is shown in Fig. 2.

25 The air-flues 7 lead directly into the air-regenerators, and the connecting-flues 13 con-

verge inwardly to points beneath the gas-flues 10 and thence lead to the center of the furnace, where they communicate through side openings with the air-inlet flues at the outer 5 sides of the gas-inlets.

The vertical portions 14 of the inlet-flues are provided with blind-openings 15, which lead into the tunnel beneath the slag-hole 16. As the blocks wear down at the top of the 10 ports 8 and 9 any glass that runs down into these ports may thus be taken out through these blind-openings.

The furnace is operated in the usual manner, the damper 17 of stack-flue 18 being regulated so as to keep a pressure in the furnace-chamber in the usual way. The heated air and gases entering the furnace burn and spread throughout the chamber, and the products pass off through the other set of regenerators through the chimney, the direction of the gases being reversed, as desired. 15 20

To prevent the flame from the regenerator-ports from overheating the nearest pots, I preferably employ shade-walls 19 at the ends 25 of the ports and between them and the adjacent pots.

In order to keep the floor 20 above the regenerators cool for the workmen, I provide an air-space 21 between it and the tops of the regenerative chambers, as shown in Fig. 4. Air circulates through this insulating-space and keeps the floor comparatively cool. 30

The advantages of my invention flow from the location of the regenerator-ports within 35 the lines of the pots, and more specifically from the external regenerative system, with the compact arrangement of the flues leading into the furnace through the ordinary tunnel.

The system is easily applied to an old furnace and is cheaper to build than the ordinary regenerative pot-furnace. A compact arrangement is afforded, while the output of the furnace is increased by allowing the full 40 number of pots to be used.

A circular, elliptical, or rectangular furnace may be used, and the regenerators may be located at opposite sides of the furnace or directly beneath it, and many other changes 45 may be made in the form and arrangement of the regenerators, their connections, and the 50 other parts of the furnace without departing from my invention.

I claim—

1. A regenerative glass-pot furnace having two separated ports opening into the furnace-chamber, a line of pots surrounding said ports, regenerators having flues connected to the ports, and mechanism for reversing the direction of flow through the regenerators, ports, and furnace; substantially as described. 55 60

2. A regenerative glass-pot furnace having a plurality of ports opening into the furnace-chamber, a row of pots surrounding said ports, regenerators each having a flue leading to one of said ports and also arranged to be connected to an outlet-flue, and valve mechanism for reversing the flow of gases through said regenerators, ports and furnace; substantially as described. 65

3. A regenerative glass-pot furnace having four ports opening into the furnace-chamber, a row of pots surrounding the ports, four regenerators, each having a connection to one of said ports, and also a connection leading to a stack-flue, said regenerators being arranged in pairs and having suitable gas and air connections, and mechanism for reversing the flow through the pairs of regenerators, their connections at the furnace; substantially as described. 70 75 80

4. A regenerative glass-pot furnace having a plurality of ports opening into the furnace-chamber, a row of pots surrounding the ports, regenerators exterior to the furnace and each having connections to one of said ports, and mechanism for reversing the direction of the flow through said regenerators, ports and furnace; substantially as described. 85

5. A regenerative pot-furnace having four ports opening into the furnace-chamber, a row of pots surrounding said ports, four regenerators external to the furnace, flues leading from the regenerators to the furnace-ports and arranged in pairs one above the other, and mechanism for reversing the direction of the flow through said regenerators, the ports, and furnace; substantially as described. 90 95

In testimony whereof I have hereunto set my hand.

HENRY L. DIXON.
